WATER SKI TIP

Robert L. Sackett, 1233 Shafter St., San Diego, Calif.

Filed Sept. 14, 1964, Ser. No. 81,706

Term of patent 14 years

(Cl. D71—1)

Fig. 1

Fig. 2

Fig. 3

Fig. 4

Fig. 5

FIGURE 5 is a sectional view taken on line 5—5 of FIGURE 2.

The portions of a ski shown in broken lines are included for illustrative purposes only.

I claim:

The ornamental design for a water ski tip, as shown and described.
